DESIGN FOR A BICYCLE LOCK

Solomon Wise, Shaker Heights, Ohio

Application November 23, 1936, Serial No. 66,089

Term of patent 14 years

To all whom it may concern:

Be it known that I, Solomon Wise, a citizen of the United States, residing at Shaker Heights, in the county of Cuyahoga and State of Ohio, have invented a new, original, and ornamental Design for a Bicycle Lock of which the following is a specification, reference being had to the accompanying drawing, forming a part thereof, in which:—

lock looking toward the front of the same, the lock being shown in unlocked position.

I claim:

The ornamental design for a bicycle lock as shown and described.

SOLOMON WISE.
